(57) **CLAIM**

The ornamental design for a pump for liquids, as shown and described.

DESCRIPTION

FIG. 1.1 is a top plan view of a pump for liquids according to the design;

FIG. 1.2 is a right side elevation view thereof;

FIG. 1.3 is a perspective view thereof;

FIG. 1.4 is a front elevation view thereof; and

FIG. 1.5 is a back elevation view thereof.

The broken line showing of portions of the pump is for the purpose of illustrating environmental structure and forms no part of the claimed design.
